UNITED STATES PATENT OFFICE.

GUSTAF IVAR BARCLAY, OF DETROIT, MICHIGAN, ASSIGNOR TO DETROIT STEEL PRODUCTS COMPANY, OF DETROIT, MICHIGAN, A CORPORATION OF MICHIGAN.

SASH-OPERATING MECHANISM.

Application filed December 6, 1926. Serial No. 152,977.

The invention relates to sash operating mechanism and refers more particularly to power mechanism for operating sashes. The invention has for some of its objects 5 the provision of an improved mounting for the motor providing for locating the power shaft of the motor parallel to the drive shaft forming part of the operative connection between the motor and a sash; the provision 10 of an improved device for actuating the switch which controls the operation of the motor; the provision of an improved attachment means between the pull rod operatively connected to a sash and the flexible 15 connection such as a chain for actuating the pull rod; the provision of an improved support for the idler over which the flexible connection runs, as well as the portion of the pull rod connected to the flexible connection; and the provision of a brake for 20 retarding the rotation of the drive shaft in a direction to close a sash and thereby reduce the speed of closing of a sash and the force with which a sash contacts with its 25 frame, as well as prevent damage to the parts of the mechanism. With these as well as other objects in view, the invention resides in the novel features of construction and combinations and arrangements of parts 30 as more fully hereinafter set forth.

In the drawings:—

Figure 1 is a perspective view of a sash operating mechanism, embodying my invention;

35 Figure 2 is a side elevation of a portion thereof;

Figure 3 is an end view of Figure 2;

Figures 4, 5 and 6 are enlarged side elevations of portions of the operating mechanism;

40 Figure 7 is a cross section on the line 7—7 of Figure 4;

Figure 8 is a plan view of Figure 5;

Figure 9 is an end view of Figure 6;

45 Figures 10 and 11 are respectively a plan view and a side elevation of the motor mounting; and

Figure 12 is an enlarged cross section on the line 12—12 of Figure 2.

50 The mechanism herewith shown is designed particularly for operating vertical swinging sashes in unison and comprises longitudinally movable pull rods 1 which are operatively connected to the sashes to 55 open and close the same upon movements in

opposite directions, flexible connections 2 secured to the pull rods, gearing 3 for actuating the flexible connections and an electric motor 4 for driving the gearing. The flexible connections are in the nature of chains 60 having their ends connected to the pull rods and running over the idler sprockets 5 and the driving sprockets 6, which latter form part of the gearing 3. The gearing 3, in addition to the driving sprockets 6, comprises reduction gears including the worm wheel 7 meshing with the worm 8 secured upon the drive shaft 9, this drive shaft having secured at one of its ends the gear 10 which meshes with the gear 11 upon the 70 power shaft 12 of the motor. The gearing 3 is suitably housed within the housing 13 which may be supported upon a column by means of the brackets 14.

The motor is carried by the housing 13 75 and in order to provide for locating the power shaft of the motor parallel to the drive shaft of the gearing so that the meshing gears upon the two will properly operate the motor is adjustably mounted upon 80 the housing. In detail, 15 is a plate to which the motor is secured by means of the bolts 16 and nuts 17, this plate having, as shown particularly in Figure 10, the transverse elongated openings 18 for engagement 85 by the bolts to thereby permit transverse movement of the motor relative to the plate. The plate 15 is supported from the housing 13 so that it may be angularly adjustable 90 relative thereto. Furthermore, the plate is supported by a three-point suspension which comprises the three plugs 19 threadedly engaging the arms 20 of the housing 13 and having flats 21 at their lower ends for engagement by suitable tools such as wrenches. 95 22 are bolts which extend freely upwardly through the studs. These bolts extend upwardly through the plate 15 and have heads at their lower ends below the plate for supporting the same and are engaged at their upper ends by the nuts 23. With this arrangement the plugs 19 may be adjustably threadedly engaged by the arms of the housing 100 while the nuts 23 are slightly loosened to provide for locating the power shaft of the motor in parallelism to the drive shaft of the gearing. The nuts 23 may then be tightened.

To connect the ends of the chains 2 to the pull rods 1, I have provided the attachment 110

member 24 which has the stud 25 for threading into the end of the pull rod 1. One end of the chain extends in alignment with the pull rod and is connected thereto by means of the pin 26, the attachment member also preferably having upstanding projections 27 for engaging behind the adjacent link pivots and assisting in connecting this end of the chain to the pull rod. The attachment member also has the upstanding lug 28 which is provided with a bore extending parallel to the pull rod 1 for engagement by the eye bolt 29 connected to a link at the other end of the chain. 30 are nuts threaded upon the eye bolt and at opposite ends of the lug 28 for adjustably holding the eye bolt to the attachment member and 31 are lock nuts also threaded upon the eye bolt and abutting the nuts 30. With this arrangement it will be seen that one end of the chain is secured to the pull rod in alignment therewith, while the other end of the chain extends adjacent and parallel to the pull rod and is adjustably connected thereto to take up slack in the chain.

To support the idler sprockets 5 and the portions of the pull rods connected to the chain I have provided the plate 32 which is secured to an I-beam of the building and 33 carries the bifurcated member which is mounted an idler sprocket. An anti-friction roll 34 is mounted between the lower ends of the arms of this bifurcated member and is preferably shaped to fit the contour of the pull rod, the latter resting upon the former. Thus it will be seen I have provided a common means for supporting both an idler sprocket and the portion of the pull rod connected to the flexible connection.

35 is an electric switch mounted upon the housing 13 for controlling the flow of electric current to the motor 4. This switch is of the rotary type and is of standard construction, no invention being claimed for the same by applicant. 36 is a lever arm connected to the rotary part of the switch, this lever arm having openings therein for the passage of the upper and lower portions of the chain 2. 37 and 38 are devices mounted respectively upon the upper and lower portions of the chain 2 for contacting with the lever arm to throw the switch when the sashes have approximately reached their limits of closing and opening movements respectively. These devices are alike and therefore but one will be described in detail. 39 is the base of the device having integral transverse projections 39' for extending between the pivots of alternate links of the chain. This base is clamped to the chain by means of the bolt 40 which extends through the base and between the pivots of the intermediate chain link, the nut 41 threaded upon the bolt, and the clamping

plate 42 secured against the side of the chain opposite that occupied by the base. The base has the transverse lug 43 which is provided with the transverse threaded opening 44 for engagement by the externally threaded plug 45 having at its rear end the flats 46 for engagement by a suitable tool such as a wrench. 47 is a set screw threaded into the lug 43 and adapted to engage the plug to hold the latter in its positions of 70 rotative adjustment relative to the lug. 48 is a plunger slidably engaging in the plug 45 and adapted to abut the lever arm 36. This plunger has a reduced stem 49 which extends rearwardly through and slidably engages the rear end of the plug 45 and 50 is a suitable device such as a cotter pin extending through the rear end of the stem for preventing accidental disengagement of the plunger from the plug under the action of 80 the coil spring 51 which is located within the plug and around the plunger stem and abuts the rear end of the plug and the shoulder upon the plunger formed between the main portion thereof and the stem. With this arrangement either the device 37 or 38 may be approximately located upon the chain to locate its plunger 48 to engage and actuate the lever arm 36 at approximately the correct time. To more accurately control the time 90 of actuating the lever arm the plug 45 may be longitudinally adjusted relative to the base of the device and to prevent breaking or damaging of the parts the plunger is yieldably held in a predetermined position 100 so that if the mechanism does not stop immediately upon throwing the switch the plunger can yield.

For the purpose of retarding the movement of the mechanism during the closing movement of the sashes, I have provided a brake which is automatically operable. This brake is located upon the extension 52 of the drive shaft 9 and comprises the friction base 53 located concentrically of the extension and secured to the housing 13, the friction washer 54 surrounding the extension and adapted to engage the base 53, the friction nut 55 having its inner end adapted to engage the friction washer 54, the worm 56 having teeth engaged by those of the nut and the coil spring 57. The worm surrounds and is secured to the extension 52 by means of the transverse pin 58 so that this worm rotates with the extension of the drive shaft. The coil spring surrounds the worm and has one end hooked around the pin 58 and the other end extending transversely into the nut 55. This nut has a series of bores in its outer end alternatively engageable by the transverse end of the coil spring for varying the degree of tension upon the latter. The inclination of the teeth is such that upon rotation of the drive shaft in a direction to raise the sashes and consequent 130

rotation of the worm relative to the nut the nut is moved away from the friction washer, the strength of the coil spring being such as to provide for a relative rotation of 5 the worm and nut. At this time the direction of rotation is such that the tension of the spring is increased. Upon rotation of the drive shaft in the reverse direction to close the sashes and consequent rotation of 10 its extension the worm rotates relative to the nut to force the nut against the friction washer at which time the coil spring is under compression and tends to rotate the nut to move the same away from the washer, 15 the arrangement being such that the nut operates against the friction washer to force the same against the base to frictionally retard rotation of the extension and drive shaft without gripping to stop the rotation.

20 What I claim as my invention is:

1. In sash operating mechanism, the combination with a motor operatively connected to a sash, of a switch for controlling the operation of said motor and an adjustable and 25 yieldably movable device carried by the connection between the motor and sash dependent upon the operation of said motor for actuating said switch.

2. In sash operating mechanism, the combination with a motor and means including 30 a flexible connection for operatively connecting said motor to a sash, of a switch for controlling the operation of said motor, and a device carried by said flexible connection 35 for actuating said switch, said device including a base, a member adjustably mounted upon said base, and a plunger carried by said member.

3. In sash operating mechanism, the combination with a motor and means including 40 a flexible connection for operatively connecting said motor to a sash, of a switch for controlling the operation of said motor, and a device carried by said flexible connection 45 for actuating said switch, said device including a base, a member adjustably mounted upon said base, a plunger slidably engaging said member, and means for yieldably forcing said plunger in one direction relative 50 to said member.

4. In sash operating mechanism, the combination with a motor and means including 55 a chain for operatively connecting said motor to a sash, of a switch for controlling the operation of said motor, and a device carried by said chain for actuating said switch, said device including a base mounted upon 60 said chain, a plug adjustably threadedly engaging said base, a plunger extending within and slidably engaging said plug, and a coil spring within said plug and abutting 65 said plunger for yieldably forcing said plunger in one direction relative to said plug.

5. In sash operating mechanism, the com-

bination with a pull rod operatively connected to a sash and a chain for longitudinally moving said pull rod, of means for securing said chain to said pull rod including a member mounted upon said pull rod 70 and provided with a projection engageable behind one of the link pivots at one end of said chain, an eyebolt connected to one of the link pivots at the opposite end of said chain and movable longitudinally relative to said 75 member, and means for adjusting said eyebolt longitudinally relative to said member.

6. In sash operating mechanism, the combination with a pull rod operatively connected to a sash and a chain for longitudinally moving said pull rod, of means for connecting said chain to said pull rod with one end of said chain in direct alignment with 80 said pull rod and the other end of said chain arranged in substantial parallelism with said pull rod and connected thereto adjacent the connection of said first mentioned end with the pull rod.

7. In sash operating mechanism, the combination with a pull rod operatively connected to a sash, a flexible connection secured to said pull rod for actuating the same, and an idler over which said flexible connection runs, of a common means for supporting said idler and the portion of said 95 pull rod connected to said flexible connection.

8. In a sash operating mechanism, the combination with a drive shaft operably connected to a sash to open and close the same, 100 of a motor for driving said drive shaft, and a brake automatically operating to retard rotation of the drive shaft during the closing of the sash.

9. In a sash operating mechanism, the combination with a motor and means including 105 a flexible connection for operatively connecting said motor to a sash, of a switch for controlling the operation of said motor and an adjustable and yieldable device carried by the flexible connection aforesaid and dependent upon the operation of said motor for actuating said switch.

10. In a sash operating mechanism, the combination with pull rod operatively connected to a sash and a chain for longitudinally moving said pull rod, of means for connecting said chain to one end of said pull rod with one end of said chain in alignment with said pull rod and the other end of said chain adjustably connected to the end aforesaid of the pull rod and extending in substantial parallelism with said 120 pull rod.

11. In a sash operating mechanism, the combination with a drive shaft operatively connected to a sash, of a motor for driving said drive shaft, a flexible member for operatively connecting said motor to the sash, 125 a switch for controlling the operation of 130

said motor, means carried by said flexible member for actuating said switch and means automatically operating to retard rotation of said drive shaft in one direction.

5 12. In a sash operating mechanism, the combination with a pull rod operatively connected to a sash and a chain for longitudinally moving said pull rod, of means for connecting the opposite ends of said chain 10 to one end of said pull rod.

13. In a sash operating mechanism, the combination with a pull rod operatively connected to a sash and a chain for longitudinally moving said pull rod, of a member secured to one end of said pull rod, and means 15 for securing the opposite ends of said chain to said member.

14. In a sash operating mechanism, the combination with a pull rod operatively connected to a sash and a chain for longitudinally moving said pull rod, of a member secured to one end of said pull rod, means for 20 securing one end of said chain to said member in alignment with the pull rod, and

means for adjustably securing the opposite 25 end of said chain to said member adjacent the securing means aforesaid.

15. In a sash operating mechanism, the combination with a pull rod operatively connected to a sash and a chain for longitudinally moving said pull rod, of a member secured to one end of said pull rod having a projection, means for securing one end of 30 said chain to said pull rod, and means for adjustably securing the opposite end of said 35 chain to said projection.

16. In a sash operating mechanism, the combination with a pull rod operatively connected to a sash and a member for longitudinally moving said pull rod, of means for 40 connecting said member to one end of said pull rod with one end thereof in substantially the same horizontal plane as said rod, and means for connecting the opposite end 45 of said member to the end aforesaid of the pull rod.

In testimony whereof I affix my signature.

GUSTAF IVAR BARCLAY.
